UNITED STATES PATENT OFFICE.

DIRK LELY, JR., AND HENDRIK FILIPPO, OF EINDHOVEN, NETHERLANDS, ASSIGNEES
TO NAAMLOOZE VENNOOTSCHAP PHILIPS' GLOEILAMPENFABRIEKEN, OF EINDHOVEN, NETHERLANDS.

ARRANGEMENT FOR REDUCING THE STARTING VOLTAGE OF DISCHARGE TUBES WITH A GASEOUS FILLING.

Application filed January 29, 1923, Serial No. 615,785, and in the Netherlands February 15, 1922.

This invention relates to an improved arrangement for reducing the starting voltage of discharge tubes with a gaseous filling, more particularly to those tubes containing

5 a rare gas, in which a discharge between main electrodes is initiated by an auxiliary discharge between an auxiliary electrode and one of the main electrodes.

By applying such an auxiliary discharge 10 the starting voltage of the main discharge is reduced and the present invention has for its object to further reduce this voltage and to improve the efficiency of the tube.

According to the invention an auxiliary 15 electrode arranged opposite to one of, or to both main electrodes in a discharge tube with a gaseous filling, is connected in series with a condenser. In parallel to this condenser a high resistance may also be connected. The starting voltage of the main 20 discharge is thereby reduced to a greater extent and moreover the efficiency of the tube is improved.

The invention may be applied to any 25 discharge tube in which an auxiliary discharge is resorted to so as to initiate a main discharge in a rare gas or a mixture of rare gases. The main discharge may be of different character for instance an arc-discharge or a glow-discharge.

In the accompanying drawing some examples of different connections according to the invention are shown.

Fig. 1 shows a discharge tube for glow 35 discharge, in which a condenser is connected in series with the auxiliary electrode and

Fig. 2 shows a tungsten arc-lamp provided with one auxiliary electrode with which a condenser is connected in series; in parallel 40 to this condenser a high resistance is connected.

In Fig. 1, 1 is the glass bulb, containing a suitable gaseous filling such as neon or any other rare gas or mixture of rare gases. The 45 main electrodes 2 and 3 are supported by the leading-in wires, which are fused into the stems 9 and 10. The auxiliary electrodes 4 and 5 are likewise supported by the leading-in wires and are connected via the condensers 6 and 7 to the conductors 8 to which the main electrodes are also connected. The conductors 8 are connected to a lighting cir-

cuit of suitable voltage, a network of 220 volts for continuous current for example. A stabilizing resistance 11 is connected in series to the main electrodes.

In Fig. 2 in which a tungsten arc lamp is illustrated corresponding parts are indicated by references similar to those used in Fig. 1.

In the arrangement according to Fig. 2 a high resistance 12 is connected in parallel to the condenser 6.

The favourable effect of the arrangement according to the invention is apparently due 65 to the charging current, occurring on switching on the condenser.

The strength of the current of the auxiliary discharge is thereby temporarily high; apparently a cloud of ions is produced, diffusing to the point where the main discharge is to be initiated, and thus facilitating the starting of the main discharge. In the case of a continuous current the diffusion-process of the ions is assisted by the 75 disappearance of the field immediately after switching on.

It is clear that the invention is particularly applicable where a continuous current is used, as in the case of connecting to a network for continuous current the charging-current of the condenser will always reach the same maximum value, whereas in the case of a lighting circuit for alternating current the value of the charging-current would 80 depend on the moment of switching on, in other words on the momentary value of the voltage.

When connecting to a lighting-system for continuous current there is another advantage, 90 namely that shortly after switching on, the auxiliary discharge ceases entirely and consequently no longer consumes energy.

According to a second feature of the invention a high resistance 12 is connected in parallel to the condenser whereby on the one hand, the charging-current is limited and on the other hand the condenser automatically loses its charge after being put out of circuit, which is desirable in order to provide 100 for a charging-current of sufficient value when switching on afresh.

Switches 13, 14 and 15 are inserted in the auxiliary electrode circuits for control

purposes. Once the main discharge is started the condensers may be disconnected from the circuit by opening these switches.

For the same purpose it is preferable that when manufacturing the condenser care should be taken that the leakage-resistance between the coatings does not reach too great a value.

What we claim is:

10. 1. A combination of a gas-containing discharge tube having discharge electrodes, an auxiliary electrode in proximity to at least one discharge electrode and a condenser, connected in series with the gap between the said auxiliary electrode and the correspond-

ing discharge electrode and the current supply.

2. A combination of a gas-containing discharge tube having discharge electrodes, an auxiliary electrode in proximity to at least one discharge electrode, a condenser connected in series with the gap between the said auxiliary electrode and the corresponding discharge electrode and the current supply, and a high ohmic resistance connected in parallel to said condenser.

In testimony whereof we affix our signatures.

DIRK LELY (JUNIOR).
HENDRIK FILIPPO.
